UNITED STATES PATENT OFFICE

MORRIS ISAACSON, OF BROOKLYN, NEW YORK

COMBINATION BOOK REST AND STAND

Application filed December 8, 1931. Serial No. 579,674.

This invention relates to book rests adapted for the use and convenience of persons in sitting or reclining positions, and is an improvement of my patent for adjustable book ⁵ rests issued on September 1, 1931 Patent No. 1,821,060.

One of the objects of this invention is to relieve a person lying in bed or sitting in a chair of the necessity of holding in his ¹⁰ hands a book he is reading. Another object is to provide, in a device of this kind and in combination with the stand thereof, a table positioned handily with respect to the reader and whereupon can be placed books ¹⁵ or other articles to which ready access can be had. A further object of my invention is to provide, in a book rest of this type, adjusting means for readily varying the position and angle of the book to suit the ²⁰ reader, and adjustable clamping means to enable the device to be secured to different- ly positioned and variously shaped and sized supports.

It is still another object of this invention ²⁵ to enable the vertical adjustment of the stand to be made with little effort and with a minimum of noise. A further object is to provide means to limit the rotary movement of the book supporting member about ³⁰ its horizontal axis to an arc of approximately 90 degrees, so as to keep the book from sliding down or toppling over.

Another object of my invention is to provide means for vertically adjusting a reflector light without interfering with the horizontal movement of the book rest, and for keeping the conducting wire protected and free from entanglement.

And still a further object is to provide ⁴⁰ for books of different thicknesses, simple and secure means to hold and support the pages of the book to prevent a downward sag, and to keep the book fixed in its open position.

⁴⁵ Other objects, features and advantages will appear from the drawings, and the description hereinafter given.

Referring to the drawings:

⁵⁰ Figure 1 is a perspective view of the combination book rest and stand comprising my

invention, showing an open book thereon and a closed book on the table; and illustrating the operative and inoperative positions of the page holders.

Figure 2 is a longitudinal section of the ⁵⁵ device, showing two positions of the book supporting member.

Figure 3 is a sectional elevation of Figure 2 taken along line 3—3.

Figure 4 is a rear view of the back rest ⁶⁰ pivotally connected to the vertically adjust- able supporting rod.

Figure 5 is an end elevation of the book supporting member resting on an horizontal surface, the base plate and supporting rod ⁶⁵ 65 being removed.

Figure 6 is a section of the bracket ar- ⁷⁰ rangement of Figure 5 taken along line 6—6.

Figure 7 is a perspective of the adjustable ⁷⁰ clamp attached to the arm of a chair, show- ing three relative positions of the clamp and the supporting rod associated with the book supporting member.

In the drawings, the supporting member ⁷⁵ 10, which is the support proper for the book 11, comprises a back rest 12 and a flanged bottom rest 13 through which extends the telescopic page holders 14. These consist of two slidably engageable tubes 15 and 16, to ⁸⁰ the former of which is attached the knob 17 and the spring member or yieldable finger 18. The helical spring 19, which can also be an elastic band, is secured to the inner tube 15 at some suitable point such as 20, the ⁸⁵ other end being attached to the outer tube 16 in some suitable way such as by engage- ment with the pin 21.

On the under side of the back rest 12 are two parallel rails 23 and 24, shown in the ⁹⁰ drawings as channel bars suitably secured to the member 10. In slidable engagement with these rails is the base plate 25, serving as an adjustable support for said member 10. This plate contains, preferably integral ⁹⁵ therewith, the extension 26 adapted for frictional engagement with the bifurcated upper end 27 of the supporting rod 28. To procure proper frictional engagement, the washers 29 are inserted between the ears of said ¹⁰⁰ 100

bifurcated portion and said extension 26; and the carriage bolt 30 with square shank 31 is engageable with the wing nut 32. The slit 33 in the said rod 28 gives a certain degree of elasticity to the structure, resulting in a flexible arrangement.

The extension piece 26 contains projections or stops 34 and 35 which are abuttable with rod 28 to limit the rotary movement 10 of member 10 around its axis 36 to an arc of about 90 degrees, stop 34 preventing movement of said member beyond its vertical position to remove the possibility of a book toppling over, and the stop 35 preventing movement beyond its horizontal position to prevent a book from sliding down rearwardly.

The reflector light 37 is secured to the hollow stem 38 which is pivotally attached to 20 the tubular elbow 39, the wing nut 40 being used to frictionally hold stem 38 in its projected position. The said elbow 39 contains, in threaded engagement therewith, the hollow extension tube 41, which is in slidable 25 engagement with the guiding member or outer tube 42 secured to the back side of member 10 and preferably positioned within a groove therein. The spring attachment 43 is affixed to outer tube 42 and is yieldably 30 and frictionally held against the extension tube 41 through the opening 44 in said outer tube.

Inserted in the hollow extension rod 43a is the rod 28, the expanded portion or collar 35 44a of which rests upon the upper end of said extension rod, the annular grooved portion 45 being adapted to receive and frictionally engage the set screw 46a. It is thus obvious that by a manipulation of said set 40 screw, the rod 28 and consequently member 10 can be frictionally held fixed against rotary movement about the vertical axis of rod 43a.

The stand 46 contains a tubular upright 45 47 into which is slidably inserted the extension rod 43a having its closed bottom end 48 resting upon the helical spring 49 contained within the said upright 47. This spring serves not only the function of a 50 cushioning device to prevent a sudden drop of rod 43a and a noisy impact with the base of the stand, but also serves to facilitate the raising of the extension rod, due to the upward pressure exerted by the spring when 55 in compression. The set screw 50 is adapted to frictionally engage rod 43a to hold it in a predetermined vertical position against upright 47.

Slidably mounted over the extension rod 60 43a is the table 51 and its supporting bracket 52 which is frictionally and slidably held in place along said rod 43a by the set screw 53. This table is used to support a book or other article thereon, and being on the stand 65 and adjustable vertically and rotatably

about the axis thereof, it can be made sufficiently handy to a person using this device to enable him to have ready access to another book that he may wish to place on the book rest.

It will be noted that an electric conductor 54 can be inserted in the extension tube 41 to pass through the elbow 39 and the stem 38 to the reflector light. As the tube 41 underlies the rails 23 and 24, and the bottom thereof extends below rail 24, the wire 54 which enters the said bottom end is housed by tube 41, is free from interference or engagement with the base plate 25 or extension piece 26 during a horizontal movement of member 10, thereby preventing entanglement or cutting of this wire.

The page holders 14 are adjustable to books of different thicknesses, as the telescopic arrangement permits the distance between the finger 18 and the back rest to be varied as may be necessary. As the inner tube 15 extends for a distance within the outer tube 16, the two are always in axial alignment, producing a firm construction and practically preventing lateral movement. To bring the page holders into their inoperative positions, the knob 17 is turned, thereby rotatably carrying the finger 18 with it and out of contact with the pages of the book and to its position against the front surface of the bottom rest 13.

The spring arrangement 19 within the tubes of the page holder not only serves to hold the book in its open position, but also helps the fingers 18 to keep the book firmly in place against the back rest. Should the book be a thick one extending out beyond the bottom rest 13, the extended portion of the tubes 15 will underly the protruding portion of the book and help to support it. The fact that a considerable portion of the inner tube 15 extends into and is supported by the outer tube 16, and the entire page holder assembly 14 is supported by the bottom rest, results in a construction sufficiently strong to support a book of considerable weight.

To aid in keeping the book from toppling over when member 10 is in a vertical position, the elastic member 55 is employed. The ends of this member are secured to the back of the member 10, a book being held in place against the back rest by member 55 passing thereover through a pair of the slots 56 at the sides of the back rest. As there are a number of these slots running lengthwise of the sides of said back rest, this elastic holding means can be adapted to books of different sizes.

The book rest portion proper, or member 10, can be removed from the stand and placed upon a table if desired, as illustrated in Figure 5. For this purpose, the support 57 is employed, which is pivotally connected

to the back rest by an arrangement comprising the brackets 58, the carriage bolts with square shanks 59, the washers 60, and nut 61 (see Figure 6). It will be noted that each 5 of the said brackets 58 contains a portion attached to the back rest and an outwardly extending portion bent back almost upon itself to form two parallel walls 58a and 58b to receive, for frictional engagement, an upper 10 end of the support 57 and the washers 60. This simple construction enables a frictional and pivotal adjustment of the support 57 to be made to suit the user, and permits the 15 inclination of the member 10 to be varied at will.

To enable the book rest portion to be attached to a chair or other suitable support, the adjustable clamp 61a is used (See Figure 7). This contains the clamp bolts 62 20 having thereon the padded saddles 63, the braces 64 each having an arm 65 to support said bolts, and a parallel arm 66, both of said arms 66 being joined by the cross bar 67 to which is attached the spherical rod 25 holder 68. This holder has three mutually perpendicular intersecting holes extending therethrough and meeting in the center thereof to form an internal chamber which communicates with the threaded hole into 30 which the set screw 69 extends. This arrangement permits the clamp 61a to be suitably supported in either an horizontal or vertical position so as to enable the supporting rod 28 to be vertically received by one of 35 said three holes. As the set screw 69 extends into the said chamber in the spherical rod holder 68, it will serve to frictionally hold the rod 28 in its projected position while in any of the said three holes, without 40 the use of any other set screws.

The combination of adjustable features in this device results in an exceedingly flexible arrangement, rendering a book supported thereby capable of being easily and readily 45 brought into any and every position suitable to the needs and convenience of the reader, and limited only by the dimensions of the structure.

Other and different mechanical embodiments can be employed within the scope of 50 the appended claims, without departing from the spirit of this invention.

What I claim is:

1. In a book supporting device, the combination of a back rest, a flanged bottom rest attached to said back rest, page holding means extending through and supported by said bottom rest, two parallel horizontally disposed rails secured to the rear of said 55 back rest, a base plate in slidable engagement with said rails, a supporting rod pivotally secured to said base plate, a recess at the rear of said back rest and underlying and extending in a direction transverse to said rails, and means positioned within said

recess for housing electric conductors for a suitably positioned lamp.

2. In a book supporting device, the combination of a book rest proper, a base plate thereunder, a supporting rod in pivotal engagement with said base plate, an adjustable clamp containing a spherical holder for said rod and containing three mutually perpendicular intersecting holes to slidably receive said rod, said holes running through said holder and forming an internal chamber in the center thereof, a threaded hole communicating with said chamber, and a set screw in engagement with said hole and extending into said chamber to frictionally hold the said supporting rod therein against movement.

3. In a book supporting device, the combination of a book rest proper, a base plate thereunder, a supporting rod in pivotal engagement with said base plate, an adjustable clamp having two parallel members, two clamp bolts supported thereby, a cross bar joining said members, a spherical holder for said rod attached to and extending outwardly from said cross-bar, said holder containing three mutually perpendicular intersecting holes to slidably receive said rod, said holes running through said holder and forming an internal chamber in the center thereof, a threaded hole communicating with said chamber, and a set screw in engagement with said hole and extending into said chamber to frictionally hold the said supporting rod therein against movement.

4. In a book supporting device, the combination of a book rest proper, two horizontally disposed parallel rails secured to the rear of said book rest, a base plate in slidable engagement with said rails, a supporting rod in pivotal engagement with said base plate, a recess at the rear of said back rest and underlying and extending in a direction transverse to said rails, means positioned within said recess for housing electric conductors for a suitably positioned lamp, an adjustable clamp containing a spherical holder for said rod and containing three mutually perpendicular intersecting holes to slidably receive said rod, said holes running through said holder and forming an internal chamber in the center thereof, a threaded hole communicating with said chamber, and a set screw in engagement with said hole and extending into said chamber to frictionally hold the said supporting rod therein against movement.

5. In a book supporting device, the combination of a pivotally mounted book rest proper, two horizontally disposed parallel rails secured to the rear of said book rest, a base plate in slidable engagement with said rails, a supporting rod attached to said base plate, a recess at the rear of said book rest and underlying and extending in a direction transverse to said rails, and means positioned within said

tion transverse to said rails, said recess extending below the lower of said rails, means positioned within said recess for housing electric conductors for a suitably positioned
5 lamp, an adjustable clamp containing a spherical holder for said rod and containing three mutually perpendicular intersecting holes to slidably receive said rod, said holes running through said holder and forming
10 an internal chamber in the center thereof, a threaded hole communicating with said chamber, and a set screw in engagement with said hole and extending into said chamber to frictionally hold the said supporting rod
15 therein against movement.

6. In a book supporting device, the combination of a book rest proper, two parallel horizontally disposed rails secured to the rear thereof, a base plate in slidable engagement with said rails and having an extension piece therein, a supporting rod pivotally connected to said extension piece, a recess at the rear of said book rest and underlying and extending in a direction transverse to
20 said rails, means positioned within said recess for containing electric conductors for a suitably positioned lamp, and an adjustable clamp containing a spherical holder for said rod and containing three mutually perpen-
25 dicular intersecting holes to slidably receive said rod, said holes running through said holder and forming an internal chamber in the center thereof, a threaded hole communicating with said chamber, and a
30 set screw in engagement with said hole and extending into said chamber to frictionally hold the said supporting rod therein against movement.

7. In a book supporting device, a back
40 rest, a flanged bottom rest attached to said back rest, means associated with said back rest for yieldably holding a book against the back rest, a base plate movably secured to the underside of said back rest, a supporting rod in pivotal engagement with said base plate, and an adjustable clamp containing a spherical holder for said rod and containing three mutually perpendicular intersecting holes to slidably receive said rod,
45 said holes running through said holder and forming an internal chamber in the center thereof, a threaded hole communicating with said chamber, and a set screw in engagement with said hole and extending into said
50 chamber to frictionally hold the said supporting rod therein against movement.

55 In testimony whereof I affix my signature.
MORRIS ISAACSON.
